UNITED STATES PATENT OFFICE.

JOHN F. SHELTON, OF FORT WORTH, TEXAS.

DESIGN FOR A WIRE FENCE.

SPECIFICATION forming part of Design No. 35,919, dated May 20, 1902.

Application filed January 21, 1902. Serial No. 90,729. Term of patent 14 years.

To all whom it may concern:

Be it known that I, JOHN F. SHELTON, a citizen of the United States, residing at Fort Worth, Texas, have invented and produced a new and Original Design for Wire Fences, of which the following is a specification, reference being had to the accompanying drawing, forming part thereof.

The figure of drawing is a side elevation of a fence-panel, illustrating my invention.

As shown in the drawing, the leading or material features of my design consist of a series of horizontal wires A, a series of wires B, curved, making a bow at the upper part and having the two legs extending to the bottom of the fence. The legs of the wires B are clamped to the horizontal wires A. The wires B form substantially semicircles above the first horizontal wire beginning at the top.

One clamp *a* (denoting the series of clamps) serves to secure two legs of the wires B, one leg of one wire and one leg of the adjacent wire. Between the first and second wires A the wires B, together with the wires A, form squares or substantially squares. Below the second wire A the legs of each wire B are crossed, forming a series of parallelograms between the second and third wires A and two series of triangles, the wires B forming the parallelograms with each other and forming one series of triangles with the second wire A and one series of triangles with the third wire A. The wires B are then clamped to the third

wire A, two legs being secured by one clamp, as shown. The legs of the wires B are then extended to the bottom of the fence and are secured to the wires A, as shown, forming substantially squares between the third and fourth and the fourth and fifth wires, one clamp securing two legs, as shown. The squares between the fourth and third and between the fourth and fifth are divided by vertical wires E. Each wire E has a ring *b* formed at the upper part and is clamped to the third, fourth, and fifth wires A in the same manner as the wires B are clamped to the wires A, except the wires E are single wires. The wires E and B form two series of rectangles between the wires A by means of the wires A.

The panel shown for illustration is for a fence. It is apparent that the design can be used for gates and similar purposes.

Having described my invention, what I claim as new, and desire to secure by Letters Patent, is—

The design for a wire fence, as herein described and illustrated in the accompanying drawing.

In testimony whereof I set my hand, in the presence of two witnesses, this 17th day of January, 1902.

JOHN F. SHELTON.
